and elongated like thin fingers of hands to be held in the society of heretofore unknown like shadowy unknown gods I sought in a place to which myself and others of our countrymen had not yet been. I approached it with a quiet mind and I was gratified to find that the atmosphere was filled with a sense of peace and quietness. I was greatly pleased with the place. Late in the evening I went into the temple to pay my respects to the deity. I was greatly gratified to find that the atmosphere

UNITED STATES 2,605,
WINDOW LOCK
J. W. Rucker, Fort
Application September 2,
2 Claims. (C)

This invention relates to securing devices, or locks, and it has particular reference to locks for balanced window sashes, and its principal object resides in the provision of a window lock capable of being installed on all types of vertically operated sashes by which the same can be secured in closed positions or in one of several adjusted positions thus affording means whereby the lower sash can be raised sufficiently to admit suitable ventilation while preventing ingress of unauthorized persons from outside.

Another object of the invention is that of providing a simple and inexpensive structure which can be readily attached to window sashes already installed and in operation thus providing greater security for occupants of the building while affording ventilation.

An object of the invention is that of providing an open grill member for hinged attachment to the lowermost sash and be capable of operation to cover the opening beneath the sash when the latter is raised and folded inwardly against the sash when the same is lowered to a closed position.

Broadly, the invention contemplates the provision of a safety securing means for dual sash assemblies operating vertically in a frame and lock the sashes in adjusted positions in said frame.

While the foregoing objects are paramount, other and lesser objects will become manifest as the description proceeds, taken in connection with the appended drawings wherein:

Figure 1 fragmentarily illustrates the junction of a pair of balanced sashes, showing the invention, in longitudinal section, installed thereon.

Figure 2 is a plan view of the invention shown attached to a pair of sashes, the latter being fragmentarily illustrated.

Figure 3 is a front view of the invention installed on a pair of window sashes, the latter being fragmentarily shown.

Figure 4 is a perspective view of the invention illustrating the bolt and actuating pin.

Figure 5 is a longitudinal cross-sectional illustration of a modified form of the invention in which is embodied a knurled knob for actuating the bolt.

Figure 6 fragmentarily illustrates, in vertical section, a window frame having a pair of sashes installed therein, and showing a grill member hingedly secured to the lower sash and depending therefrom.

Figure 7 is a front elevational view of a pair of sashes in a window frame, shown fragmentarily.

K AND GRILL *open daily 11 a.m. to 10 p.m.*
Fort Worth, Tex. *reservations 731-1111*

1949, Serial No. 113,819

Cl. 20—52) regular steel rectangular bars having a thickness of $\frac{1}{2}$ of an inch, one end being
tarily, and illustrating the lock, the keeper bar
and grill member and

Figure 8 fragmentarily shows the lower portion of a window frame, the lower sash being closed, and illustrating the grill member in inoperative position.

The invention, therefore, comprises a locking device 10 secured to the top-bar 11 of the lowermost of a pair of window sashes 12 and 13. The lock 10 cooperates with a keeper bar 14 which is attached in a vertical position to one of the stiles 15 of the upper sash 13.

The lock 10 consists of a base 16 formed with a depending flange 17 and both base 16 and flange 17 have apertures 18 for screws 19 for securing the assembly to the sash 12, as illustrated in Figures 1, 2, 3 and 4. An integral barrel portion 20 is formed on the base 16 in which a bolt 21 is slidably arranged and is adapted to engage the spaced apertures 22 along the keeper bar 14 which is attached to the upper sash 13, as shown in Figures 1, 2 and 3.

The barrel 20 has a slot 23 formed obliquely across its top, as apparent in Figure 2, through which a pin 24 projects, its inner end being rigidly fixed to the bolt 21 to provide means for actuating the latter in a spiral motion longitudinally of the barrel 20. The slot 23 defines a substantially spiral course, as well as being arranged obliquely with respect to the longitudinal axis of the barrel 20, to advance and retract the bolt 21, as the same is rotated, to engage the apertures 22 in the keeper bar 14.

In Figure 5 is illustrated a modified form of the lock 10 in which the bolt 25 therein is formed with a spiral groove 26 receiving a pin 27 which is connected interiorly of the housing or barrel 29. As the bolt 25 is rotated by the knurled head 28 it will advance or retract in the same manner as the bolt 21 is operated. The structure shown in cross-section in Figure 5 is otherwise identical with that illustrated in Figures 1 to 4 inclusive.

Hingedly connected to the lower edge 29 of the lower sash 12 is a grill 30 which has an arrangement of bars 31 within a frame structure 32. This device is illustrated more clearly in Figure 7. It is the purpose of the grill 30 to close the opening below the lower sash 12 when the latter is raised. Thus, ventilation may be enjoyed while the window is securely barred against entry therethrough from the outside.

The side members 33 of the frame 32 extend above the top members and are secured at their upper ends by suitable pins or screws 34 to brackets 35 which are attached to the lower edge 29 55 of the sash 12 so that the side members 33 will

lie along the inner sides of the window frame 36, swinging outwardly to assume the operative position shown in Figures 6 and 7, or the collapsed position shown in Figure 8 when the sash 12 is closed. The lower ends 37 of the side members 33 engage the sill 38 of the window frame 36 in front of the stool 39 when the grill 30 is in operative position below the sash 12, as in Figures 6 and 7. The grill 30 is folded upwardly against the sash 12 in its inoperative position or when the sash 12 is lowered to the closed position, as illustrated in Figure 8.

In the arrangement described the sashes 12 and 13 are locked together so that they may be arranged as a unit which will afford a limited space either above or below the combined sashes 12 and 13, if these members are operated as a unit, and the opening below the lowermost sash 12 can be closed to prevent ingress, thus locking the units and rendering them immovable but affording an opening to admit outside air to the enclosure served by the window.

Manifestly, the structure shown and described is capable of considerable modification, by persons skilled in the art, without departing from the spirit and intent of the invention or the scope of the appended claims.

What is claimed is:

1. In a grill for windows having vertically adjustable sashes in a window frame, in combination with the lowermost sash, a grill frame hingedly secured at its upper end to the lower inner

edge of said lowermost sash and swingable inwardly when said sash is lowered to closed position, the lower edge of said grill frame being engageable with the sill of said window frame when said sash is raised to cover the opening in said window frame, and means for locking said sash in raised position whereby to secure said grill frame in said opening against the said window sill.

2. In a grill for windows having vertically adjustable upper and lower sashes, in combination with the lower sash in a window frame, a grill frame hingedly attached at its upper edge to the inner side of the lower bar of said lower sash and swingable inwardly and upwardly when said sash is closed, the said grill frame having its lower edge engageable with the sill of said window frame when said lower sash is raised, and means for securing said lower sash in opened position to retain said grill frame in the opening in said window frame below said raised lower sash.

J. W. RUCKER.
